UNITED STATES PATENT OFFICE.

WILLIAM H. RANKIN, OF MANCHESTER, NEW HAMPSHIRE.

IMPROVEMENT IN AUTOMATIC MECHANISMS FOR REGISTERING THE COURSE OF SHIPS.

Specification forming part of Letters Patent No. **147,021**, dated February 3, 1874; application filed November 11, 1873.

To all whom it may concern:

Be it known that I, WILLIAM H. RANKIN, of Manchester, in the county of Hillsborough, State of New Hampshire, have invented a certain new and useful Automatic Registering Mechanism for Registering the Course of Ships, of which the following is a full, clear, and exact description, reference being had to the accompanying drawings, forming a part of this specification, of which—

Figure 1 is a plan of my automatic registering mechanism. Fig. 2 is a sectional view taken on the line *x x*, Fig. 1. Fig. 3 is a sectional view taken on the line *y y*, Fig. 1.

The nature of my invention consists in adding to an ordinary mariners' compass a dial or face made of light paper mounted on the the needle of the compass in such a manner as to act therewith, and divided into points or the usual spaces. This dial is so arranged and constructed as to be easily and readily removed from the compass whenever required, and has in connection with it a traversing perforating or marking device operated by clock-work in such a manner as to move the perforating device over the dial in a radial line, traversing from center to circumference, in twenty-four hours, and also causing the needle of the perforating device to descend and puncture the card at regular intervals. The object of my invention is to furnish a means of recording a ship's course when at sea automatically, and thus to prevent the log from being falsified, as is sometimes done, for the purpose of covering up neglect or poor seamanship on the part of the officers of the vessel.

A is a box or case inclosing my device. B is a paper card or artificial dial graduated and marked like the dial of a mariner's compass, but divided on the line of the radii into spaces to represent hours of the day and night. A card or dial of this kind is to be placed on the compass regularly once in every twenty-four hours, the old one being removed and preserved as a part of the ship's log. C C, Figs. 1 and 3, are fixed rods or guides, upon which the traversing register or perforating mechanism D slides. This register is operated by a screw, E, which is attached to the arbor of the hand-wheel of the clock R, and is so arranged that when the clock is in motion it will cause

it to traverse from the circumference to the center of the dial in twenty-four hours.

The traversing-register or perforating mechanism consists of a frame-work in which a crank-disk, F³, Fig. 3, is mounted, which disk is actuated by a small spur-wheel on shaft F, and communicates motion, through the link or pitman L, to the perforating-needle N. An intermittent motion is given to this needle by the device shown in Fig. 2, which consists of a driving-wheel and coiled spring at P, and a let-off or escapement mechanism or cam, H, attached to the shaft F, on which shaft is arranged a small gear or spur wheel, which intersects with a similar wheel mounted on the same shaft with the disk F³, and through which motion is communicated to said disk. (See Fig. 2.) This cam has a projecting point or tooth, H', as shown, which rests against pins on the disk K, being kept forcibly against one of the pins (until allowed to escape) by the action of the spring around the shaft of the wheel P, Fig. 2. This disk K is on a wheel corresponding with the third wheel of a clock, and is made to revolve by any suitable clock-work at a fixed velocity, so that the point H' of the cam H is set free at certain intervals, and, after making one revolution, is stopped by the next pin on the disk, by which it is caught, and against which it must rest until the disk has revolved sufficiently to let it escape, or until it is again set free. The cam H being on the shaft F, it is evident (see Fig. 1) that when it is allowed to revolve motion will be communicated to the disk F³, and the pricking or perforating mechanism will be caused to act—that is to say, the needle N will be instantaneously thrust downward and drawn back again as the disk F³ revolves, thus perforating the paper dial or card B, the rapid movements of the needle N not interfering with the movements of the compass needle and dial mounted on the same.

To use my device, the card is placed on the compass and the clock-work adjusted and wound up. Now, as time passes and the clock runs down (the register being on board a ship under way) the needle-carriage D or perforating mechanism will be moved radially by the clock-work and the dial be punctured at regular intervals, each interval of distance measured on any radial line corresponding to time,

and the different radial lines representing the course on which the ship is sailing. (Hour and half-hour circles may be marked on the dial or circles representing more or less time.)

It will be readily understood that by drawing lines from one puncture to another, after it has remained on the compass for twenty-four hours, the different courses upon which the ship has sailed during that time can be obtained graphically, while the circle marked on the dial would show the time during which the ship was kept on any particular course. It will also be understood that when the traversing-register or perforating mechanism has advanced to the center of the dial, or has been in operation for twenty-four hours, it must be reset, which is done by disconnecting the screw E from the clock-arbor to which it is attached, and turning the screw so as to move the perforating mechanism back on the rods or guides to its original position, or to the edge of the dial nearest the clock-work. The screw must then be connected again with said arbor preparatory to the proper operation of the device for the succeeding twenty-four hours.

I am aware that in English patent No. 787, granted to one Arthur in the year 1865, a device is described having some of the characteristics of mine, but the mechanism shown in said patent differs from my invention in many important respects. In said Arthur's mechanism a pencil is used for recording the course of the ship on a paper prepared for that purpose, which paper is arranged around a vertically-rotating cylinder provided with a magnet, the pencil being caused to move vertically on the surface of such paper by a screw operated by clock-work. One of the objections

to this arrangement is that the pencil is kept in constant or nearly constant contact with the paper, and soon wears, causing it to mark imperfectly. Another is that the friction of the pencil on the paper is liable to overcome the action of the magnet, and prevent the cylinder from turning freely; and another is that when a movement of the cylinder takes place, which is not caused by an actual change in the course of the ship the pencil being in contact with the paper on the cylinder will make an erroneous record, the extent of the error in this respect being much greater than in my invention, in which, when the compass-needle or paper disk mounted on the compass is accidentally moved, it will right itself or assume a correct position between the strokes of the perforating-needle. For this reason it has been found in practice that the record made by a needle intermittently perforating a paper-disk, as described, will register more perfectly than a pencil arranged as shown in said patent. I therefore do not claim anything whatsoever shown or described in said patent, when in and of itself considered; but

What I do claim is—

The automatic register described, consisting of the traversing perforating mechanism operated by clock-work, in combination with a mariner's compass provided with an artificial dial arranged horizontally, on which the course of the ship is registered by such perforating mechanism, substantially as specified.

WM. HENRY RANKIN.
